(57) **CLAIM**

The ornamental design for a tool case, as shown and described.

DESCRIPTION

FIG. 1 is a front elevational view of a closed tool case showing our new design in a first embodiment;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof; and

FIG. 7 is a side perspective view thereof.

FIG. 8 is a front elevational view of a closed tool case showing our new design in a second embodiment;

FIG. 9 is a rear elevational view thereof;

FIG. 10 is a top plan view thereof;

FIG. 11 is a bottom plan view thereof;

FIG. 12 is a left side elevational view thereof;

FIG. 13 is a right side elevational view thereof;

FIG. 14 is an exploded, side perspective view of the opened tool case; and,

FIG. 15 is a side perspective view of the opened tool case. The broken lines in the Figures show portions of the tool case which form no part of the claimed design.
